(57) **CLAIM**

The ornamental design for a side table, as shown and described.

DESCRIPTION

FIG. 1 is a perspective view of a side table showing my new design;

FIG. 2 is the second perspective view thereof;

FIG. 3 is a front elevational view thereof;

FIG. 4 is a rear elevational view thereof;

FIG. 5 is a left elevational view thereof;

FIG. 6 is a right side view thereof;

FIG. 7 is a top side view thereof;

FIG. 8 is a bottom plan view thereof; and,

FIG. 9 is the third perspective view showing that the side table is in a folded status.

The broken lines in the figures are for the purposes of illustrating portions of the side table, which form no part of the claimed design.
